UNITED STATES PATENT OFFICE.

CORA E. WILSON, OF CENTRALIA, WASHINGTON.

CAN-OPENER.

1,267,615.

Specification of Letters Patent. Patented May 28, 1918.

Application filed July 31, 1917. Serial No. 183,764.

To all whom it may concern:

Be it known that I, CORA E. WILSON, a citizen of the United States, residing at Centralia, in the county of Lewis and State 5 of Washington, have invented a new and useful Can-Opener, of which the following is a specification.

The invention relates to a can opener, and has for its primary object to provide 10 for an opener of this character, wherein different sizes of cans can be opened thereby, without requiring excessive manual exertion, the knife and the lever for operating the same being easily adjusted for varying sizes of cans, and the cutting of the top 15 of the can is effected without danger of injury to the operator, and the edges of the opening in said top will be perfectly smooth to eliminate jagged formation.

Another object of the invention is the provision of a can opener of this character, 20 wherein the parts thereof can be readily separated for the quick and easy cleaning of the same so as to render the opener thoroughly sanitary.

A further object of the invention is the provision of an opener of this character which is simple in construction, strong yet 25 light in weight, compact, thoroughly reliable and efficient in operation, quick in action, durable, and inexpensive in manufacture.

With these and other objects in view, the invention in its preferred embodiment consists in the features of construction, combination and arrangement of parts, as will be hereinafter fully described, illustrated in the accompanying drawing, and pointed out in the claims hereunto appended. It is to 30 be understood that while the drawing shows a practical form of the invention, the latter is not confined to the strict conformity therewith, but may be changed or modified as long as such changes or modifications 35 come within the scope of the annexed claims.

In the accompanying drawing:

Figure 1 is a perspective view of a can opener constructed in accordance with the invention, showing by dotted lines a can in 40 position for the opening thereof.

Fig. 2 is a fragmentary elevation, partly in section, showing the operating lever released for the adjustment of the knife.

Fig. 3 is a fragmentary vertical sectional view showing the fulcrum arm latched.

Fig. 4 is a vertical sectional view through the knife and guide sleeve therefor.

Fig. 5 is a detail view of the fulcrum arm.

Similar reference characters indicate corresponding parts throughout the several views in the drawing.

Referring to the drawing in detail, 5 designates a flat base preferably made from hard wood and of circular formation, although it may be made from any other suitable material and of any desirable shape. The base 5 in this instance has an offset portion 6 to which is fixed a vertical upright or frame preferably made from sheet metal bent to provide a panel 7 and a flange 8 at 70 right angles thereto, the panel at its lowermost edge being cut to provide a suitable securing ear 9 which is embedded in the upper face of the offset portion 6 of the base 5 and fastened thereto in any suitable manner. The upright or frame is preferably of the shape shown in Figs. 1 and 2 of the drawing.

Formed on the panel 7 and bent therefrom is a column 10 in which is formed a 80 vertical post 11 for adjustably supporting the cutting mechanism of the can opener hereinafter fully described.

The cutting mechanism comprises a substantially arrowhead-shaped or triangular 85 knife blade 12, formed with downward convergent beveled cutting edges 13 and the piercing point or tip 14, the wider end portion of the blade 12 being slightly arched so that it will make a circular incision or 90 kerf within the top of a can when the latter is brought into position upon the base 5 and is rotated thereon for the opening of the can. The blade 12 is offset from and integral with a sleeve 15, which is slidably 95 fitted upon the post 11, and immediately below the offset between the blade and sleeve and pivoted to said blade is the upwardly arcuate-shaped portion 16 of an operating lever 17 which at one end is adapted for 100 detachable, movable and adjustable engagement in any one of a series of elongated slots 18 formed in the flange 8 on the panel 7 next thereto, while the offset end of the lever 17 constitutes a leverage handle for 105 the manual manipulation of the lever in moving the knife blade 12 for penetrating the top of a can placed upon the base 5 for the opening of the can in a manner presently to be described.

Pivoted to the engaging end of the lever 17 is a fulcrum arm 19 which is resilient and at its free end is formed with a nib 20 for engagement in any one of a series of holes 21 formed in the panel 7 spaced from each other in a vertical row, the fulcrum arm being formed with a finger-engaging ear 22 which permits the easy disengagement of the nib 20 from a hole 21 when it is desired to adjust the knife blade 12 so that the can opener will accommodate different sizes of cans for the opening thereof, the position of the lever 17 and the fulcrum arm 19 therefor for the adjustment of the knife blade 12 being shown in Fig. 2 of the drawing, while the engagement of the fulcrum arm 19 in the panel 7 of the upright or frame is shown in Figs. 1 and 2 of the drawing.

In the operation of the can opener, the blade 12 for cutting the top of the can is vertically adjusted on the post 11 so as to permit the can, according to its size, to be placed upon the base 5 in a position substantially as shown by dotted lines in Fig. 1 of the drawing, and thereafter when the lever has been fulcrumed in its adjusted position and pressure is applied upon the lever the blade 12 is caused to penetrate the top 30 of the can and on the turning of the can the blade will cut the top for the formation of an opening therein without any ragged or jagged edges, as the edge of the opening is perfectly smooth when formed by the can opener.

In the working of the can opener there is no possibility of injury to the user, and it requires the least possible exertion for the manual operation of the can opener.

From the foregoing it is thought that the construction and manner of operation of the can opener will be clearly understood, and therefore a more extended explanation has been omitted.

What is claimed is:—

1. In a can opener comprising a base, a frame rising from said base, a post support in the frame, a cutter slidably on the post, and detachable therefrom, a lever pivoted to the cutter and having one end adjustably engageable in the frame at intervals thereof, and a fulcrum pivotally connected with the lever and adjustably and detachably engageable with the frame.

2. A can opener comprising a base, a cutter movable vertically relative to the base, a frame supported upon the base, a lever pivoted to the cutter and having one end adapted for adjustable engagement with the frame, and a fulcrum arm pivoted to the lever and having a nib adapted for detach-

able and adjustable connection with the frame.

3. A can opener comprising a support, a lever having a fulcrum for adjustable and detachable connection with the support, a vertically movable cutter pivoted to the lever and a guide for said cutter, said support being formed at intervals with slots for adjustably accommodating one end of the lever.

4. A can opener comprising a support, a lever having a fulcrum for adjustable and detachable connection with the support, a vertically movable cutter pivoted to the lever, and a guide for said cutter, said support being formed at intervals with slots for adjustably accommodating one end of the lever, and a finger engaging ear formed on the fulcrum for permitting the easy disengagement thereof from the support.

5. A can opener comprising a support, a post on said support, a cutter movable upon the post, a lever pivoted to the cutter, fulcrum means detachably and swingingly connecting the lever to the support, a sleeve on the cutter slidably embracing the post, a base for the support and forming a can rest, and a slotted flange on the support for adjustably and detachably receiving one end of the lever to guide the same in its movement.

6. A can opener comprising a base, a frame fixed to and rising from the base and forming a panel and a flange at right angles thereto, a post fixed to the panel, said flange being vertically slotted, said panel being provided with holes arranged in a vertical row, a cutter having a sleeve slidably embracing the post, a lever pivoted to the cutter and having one end adapted for adjustable engagement in any one of the slots in the flange, and a fulcrum arm pivoted to the lever and having a nib adapted for detachable and loose engagement in any one of the holes in the panel.

7. A can opener comprising a base, a vertical post on said base, a cutter movable on the post, a lever carrying the cutter, a frame having slots for the end of the lever, and a series of vertical openings adjacent to the slots, and a fulcrum arm pivoted to the lever and adapted to be engaged with any one of the openings.

In testimony that I claim the foregoing as my own, I have hereto affixed my signature in the presence of two witnesses.

CORA E. WILSON
